(57) **CLAIM**

The ornamental design for a split wires clamp, as shown and described.

DESCRIPTION

FIG 1 is a perspective view of a split wires clamp, showing my new design;

FIG. 2 is a right side elevation view thereof, the left side elevation view being a mirror image thereof;

FIG. 3 is a front elevation view thereof, the rear elevation view being a mirror image thereof;

FIG. 4 is a top plan view thereof; and,

FIG. 5 is a bottom plan view thereof.
